UNITED STATES PATENT OFFICE

101,300

DESIGN FOR A TEXTILE FABRIC

Curt Erwin Forstmann, Montclair, N. J.

Application January 27, 1936, Serial No. 60,846

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for Textile Fabrics, of which the following is a specification, reference being had to the accompanying drawing, forming part thereof, in which:

Figure 1 is a plan view of the fabric showing the design; and

Figure 2 is a cross section taken along the line 2—2 of Figure 1.

The design is three dimensional and comprises parallel stripes spaced on a background, each

stripe consisting of a pair of narrowly spaced ridges, said ridges having spaced enlarged woolly stiches arranged side by side and merging over the space between the ridges so as to form irregular four-lobed figures, the background, and the ridges between said figures having the appearance of finely interwoven meshes, and the background, the ridges between the figures, and the figures themselves, being of different elevations, ascending in their order named.

I claim:

The ornamental design for a textile fabric as shown and described.

CURT ERWIN FORSTMANN.
